UNITED STATES PATENT OFFICE.

ASHER ABRAM BROWER, OF CRESTON, IOWA.

CARPET-STRETCHER.

SPECIFICATION forming part of Letters Patent No. 417,627, dated December 17, 1889.

Application filed May 26, 1889. Serial No. 312,062. (No model.)

To all whom it may concern:

Be it known that I, ASHER ABRAM BROWER, a citizen of the United States, residing at Creston, in the county of Union and State of Iowa, have invented certain new and useful Improvements in Carpet-Stretchers; and I do hereby declare the following to be a full, clear, and exact description of the invention, such as will enable others skilled in the art to which it appertains to make and use the same.

This invention relates to carpet-stretchers; and it consists in the novel construction and combination of the parts hereinafter fully described and claimed.

In the drawings, Figure 1 is a side view of the carpet-stretcher, and Fig. 2 is a plan view of the same from above.

A is a bar provided with ratchet-teeth *a* on its upper surface and guide-grooves *a'* in its sides.

B is a prong secured to one end of the said bar and adapted to be driven into the floor close to the wall.

C is a cross-bar provided with the inclined points *c*, adapted to engage with the carpet, and D are short guides secured to the bar C on each side of bar A and engaging with the said guide-grooves.

E is a loop having its ends secured to the cross-bar C and adapted to engage with the ratchet-teeth, so that the cross-bar cannot slip back.

F is a hand-lever provided with a forked lower end *f*, which end is provided with holes *f'* about the middle of its length, and is journaled upon the loop E on each side of bar A.

G is a loop which forms a pushing-pawl for engaging with the ratchet. This loop is pivoted to the forked end of the lever above the holes *f'*.

H is a second loop, which forms a pulling-pawl, which also engages with the ratchet. This loop H is pivoted to the lower part of the forked end of the hand-lever below bar A, and *h* is a roller journaled on the ends of said loop H between the prongs of the fork of the hand-lever.

The device is double-acting. By moving the hand-lever in the direction of the arrow in Fig. 1 the loop G is caused to push against

the ratchet-teeth, and the cross-bar is dragged forward until the roller *h*, by meeting and pressing against the under side of the bar A, causes the loop E to engage with the ratchet, and thereby prevents the cross-bar from slipping back. The hand-lever is then moved in the reverse direction from the arrow in Fig. 1, the looped pulling-pawl H engages with the ratchet, and the cross-bar is again dragged forward. The device is thus operated continuously by moving the hand-lever in opposite directions alternately. The weight of the hand-lever and the other parts connected to it is usually sufficient to cause the loop E to engage with the ratchet; but at the termination of each full stroke of the hand-lever the roller *h* forces the said loop into gear, so that the device cannot let the carpet slip back. The roller also prevents the hand-lever and its pawl from rising too high and throwing too great a strain upon the short guides which slide in the grooves in the sides of bar A, and only permit the cross-bar to have a limited rocking motion. The side arms *e* of loop E are elastic, and, together with the short guides D, permit the cross-bar C to have a rocking motion, so that the lever F may rise and the loop E clear the teeth of the ratchet. The said side arms *e* are preferably crossed under the ratchet-bar and connected by the ring *e'*. This ring runs against the under side of the ratchet-bar and prevents the loop from rising too far.

What I claim is—

1. In a carpet-stretcher, the combination, with a ratchet-bar, the sliding cross-bar, and the short guides permitting the said cross-bar to have a slight rocking motion, of the pivot-loop engaging with the ratchet-teeth and provided with elastic side arms secured to said cross-bar, the hand-lever pivoted on said loop, the pushing-pawl pivoted to the hand-lever above the ratchet-bar, and the pulling-pawl pivoted to the hand-lever below the ratchet-bar, substantially as and for the purpose set forth.

2. In a carpet-stretcher, the combination, with the ratchet-bar, the sliding cross-bar, and the short guides sliding in grooves in the ratchet-bar and permitting said cross-bar to

rock slightly, of the pivot-loop engaging with the ratchet-teeth and provided with elastic side arms crossed underneath the ratchet-bar and secured to the said cross-bar, the ring 5 journaled on said crossed arms, the hand-lever pivoted on said pivot-loop, the pushing and pulling pawls pivoted to the said hand-lever above and below the ratchet-bar, respectively, and the roller journaled between the prongs

of the fork of the hand-lever below the ratchet-bar, substantially as and for the purpose set forth.

In testimony whereof I affix my signature in presence of two witnesses.

ASHER ABRAM BROWER.
